United States Patent Office.

O. E. PICKETT, OF NORTH AUBURN, AND R. S. LUCE, OF LAWSVILLE CENTRE, PENNSYLVANIA.

Letters Patent No. 74,418, dated February 11, 1868.

IMPROVED FIRE AND BURGLAR-ALARM.

The Schedule referred to in these Letters Patent and making part of the same.

TO ALL WHOM IT MAY CONCERN:

Be it known that we, O. E. PICKETT, of North Auburn, in the county of Susquehanna, and State of Pennsylvania, and R. S. LUCE, of Lawsville, in the county and State aforesaid, have invented new and useful Improvements in Fire and Burglar-Alarms; and we do hereby declare that the following is a full, clear, and exact description thereof, which will enable those skilled in the art to make and use the same, reference being had to the accompanying drawings, forming part of this specification.

Figure 1 represents a side view of our improved burglar and fire-alarm.

Figure 2 is a sectional end view, cut by the line x x , fig. 1.

Figure 3 is a partial view, showing the mode of lighting a candle with a match when the alarm is started.

Figure 4 is a top view of the alarm "set" on trigger.

Similar letters of reference indicate corresponding parts.

This invention relates to improvements in the construction of a fire and burglar-alarm, which consist in an arrangement of tripping-devices in connection with a clock-movement and bell, whereby an alarm is sounded, when, by fire or the entrance of a burglar in a house, the connection is broken by which the alarm is held; and further, in the arrangement of a device for igniting a match to light a candle or lamp when the alarm is sounded, as hereinafter described.

Within a suitable frame or box, A, is placed part of an ordinary clock-movement, of which a is the spring, b the crown-wheel, and c the escapement, connected as usual with the hammer d , to strike upon the bell B, in order to sound an alarm. Attached to the escapement c is a trip-rod, e , which holds the escapement in the wheel when the spring is wound up, by means of the point of a bent-lever trigger, g , one end of which is kept in position by a set, h , which is designed to be connected with and by a cord or wire extending through a house, and so arranged that it shall be broken by the entrance of a burglar or by fire, when the set h will be released, and thus let the trigger free from the trip-rod e , so that the spring a can act and sound the alarm.

In connection with this alarm-arrangement, a device is also provided for striking a light by the ignition of a match. A long igniting-plate, C, set in slides i i , and having a rough corrugated surface at each end for lighting a match, is attached to a spiral spring, k , in such manner that it shall be drawn within the box A, when the corrugated end of the plate is not drawn outside of the box, as shown in fig. 1, and is not held in that position by means of a lever-frame, m , that catches at one end in a notch in the side of the igniting-plate, at x , while the other end of the pawl is held by a pin on the crown-wheel b , when the alarm is wound up. The pawl m is kept in place by a spring, s . On the outside of the box a match-holder, n , is attached to a spiral spring, p , by which it is drawn out with a lighted match to light a candle, as shown in fig. 3. When the alarm is wound up and set, as before described, the corrugated end of the plate C is drawn outside of the box A, and a match is fixed in the holder n , and so placed, as shown in fig. 1, as to be held against the end of the plate, so that when the alarm is sounded the pawl m is moved, and releases the plate C, when it is drawn back by the spring k , and the corrugated surface of the end rubs and ignites the match on the holder n , which is then drawn up to light a lamp or candle, as described.

Having thus described our invention, we claim as new, and desire to secure by Letters Patent—

1. The set h , the lever-trigger g , and the trip-rod e , combined with the escapement c , the hammer d , the bell B, the wheel b , and the spring a , when arranged and operating as and for the purpose described.
2. And in combination with the alarm-device, we also claim the pawl m , the igniting-plate C, the spring s , and the match-holder n , provided with the spring p , arranged and operating as and for the purpose set forth.

The above specification of our invention signed by us, this 28th day of December, 1867.

O. E. PICKETT,
R. S. LUCE.
